UNITED STATES PATENT OFFICE

WALTER E. WILSON, OF DETROIT, MICHIGAN, ASSIGNOR TO THE ROBERT KELLER INK COMPANY, OF DETROIT, MICHIGAN, A CORPORATION OF MICHIGAN

DESIGN FOR A BOTTLE

Application filed December 1, 1932. Serial No. 46,269. Term of patent 7 years.

To all whom it may concern:

Be it known that I, WALTER E. WILSON, a citizen of the United States, residing at Detroit, in the county of Wayne and State of Michigan, have invented a new, original, and ornamental Design for a Bottle, of which the following is a specification, reference being had to the accompanying drawing, forming a part hereof.

Fig. 1 is a top plan view of a bottle embodying my new design;

Fig. 2 is a front elevation of a bottle embodying my new design; and

Fig. 3 is a bottom plan showing a bottle embodying my new design.

I claim:

The ornamental design for a bottle substantially as shown.

In witness whereof, I hereunto subscribe my name this 31st day of October, A. D. 1932.

WALTER E. WILSON.
